Patented June 21, 1921.

UNITED STATES PATENT OFFICE.

ADAM F. SCHULER, OF PHILADELPHIA, PENNSYLVANIA.

JACQUARD MECHANISM.

1,382,558.

Specification of Letters Patent. Patented June 21, 1921.

Application filed April 9, 1918. Serial No. 227,528.

To all whom it may concern:

Be it known that I, ADAM F. SCHULER, a citizen of the United States, residing in Philadelphia, Pennsylvania, have invented 5 certain Improvements in Jacquard Mechanisms, of which the following is a specification.

In utilizing Nottingham lace machines for the manufacture of filet or square mesh lace 10 it is customary at the present time to provide all the jacquard cards in duplicate for reasons which will be understood by those skilled in this particular art. One object 15 of my invention therefore, is to provide a positive, simple compact and easily applied device for adapting lace machines of the above type for the manufacture of filet or square mesh lace without necessitating the duplication of the cards, the arrangement 20 of parts being such as to require a minimum of attention under operating conditions.

These objects and other advantageous ends 25 I attain as hereinafter set forth, reference being had to the accompanying drawings in

Fig. 1 is a side elevation of the mechanism constituting my invention, illustrating it as applied to certain of the parts of a lace machine; and

Fig. 2 is an end elevation partly in section, further illustrating the invention.

In the above drawings 1 represents a portion of the frame of a lace machine which includes a cylinder 2 of square cross section 35 for supporting and feeding of the jacquard cards and this cylinder at its ends is provided with axially projecting trunnions or spindles 3 rotatably mounted in bearing members 4 carried on the ends of reciprocating rods 5 known as the cylinder pistons. The mechanism for horizontally reciprocating these pistons with the card cylinder, being well known in this art, has been omitted 40 from the drawings as it forms no part of the invention.

Projecting from one of the flat ends of the cylinder 2 adjacent the corners respectively, are four pins 6 designed to be engaged by either of two oppositely mounted clawkers 7 50 or 8 pivoted to the frame of the machine in the well known manner so as to be free to move into and out of positions in which they will coöperate with said pins to turn the cylinder. The upper clawker 7 has its 55 end adjacent the cylinder 2 made in the form of a hook with its extremity pointed or

formed with a lower inclined edge so that when in its lower position said end will drop back of one of the pins 6 of the cylinder when this has been moved by the pistons 5 to the inner extremity of its stroke, and will thereafter engage said pin as the pistons are moved outwardly to cause a quarter revolution of the cylinder.

In order to insure that the angle through 65 which this turning occurs shall be exactly what is desired and for the purpose of positioning the cylinder after such turning, an arm 9 is fixed to the piston 5 by means of a set screw 10. This arm has pivoted to 70 it an elongated bar 11 projecting substantially parallel with the clawkers so as to rest upon that one of the plane faces of the cylinder which is uppermost, the action of this bar or hammer being such that its stops 75 rotation of the cylinder in or brings it to, a definite position after each movement.

The above noted parts are those commonly employed as part of a Nottingham lace machine, and in order to adapt this for 80 the manufacture of filet lace without at the same time requiring all of the jacquard cards to be made in duplicate, I provide means whereby that one of the clawkers 7 or 8 which is operative to turn the cylinder is 85 allowed to engage the pins 6 on alternate strokes only of the pistons 5. For this purpose I mount on the frame 1 a stud 12 and 90 rotatably support on the outer end of said stud a pair of rigidly connected cams 13 and 14. The first of these, which I have designated as the star cam, is formed with four teeth or raised portions 15 and is held to the stud 12 by a nut 16. The second or ratchet cam 14 is annular in form and is 95 rigidly fixed by suitable means such as pins or screws 14^a to the first cam being made with double the number of teeth, in the present instance eight.

Each of the clawkers has fixed to it in the 100 vertical plane including the axis of the stud 12, a bracket 17 having a horizontally projecting pin or roller 18 designed to coöperate with the cam 13, each of whose teeth is so formed as to include an inclined portion 105 on one side which when it is turned acts on the pin or roller 18 to cause the clawker 7 to be moved on its pivot away from the cylinder 2 sufficiently to prevent its hooks engaging the pins 6 of the latter. The second or ratchet cam 14 is provided with a holding pawl 19 having a stem 20 acted on

by a spring 21 mounted in a recess of the tubular bracket 22 in which said stem is slidably guided. This bracket is supported from the frame 1 in any suitable manner and the pawl 19 acts to permit turning of the two cams in but one direction only.

For causing such turning a second dog or pawl 23 is pivotally mounted on an arm 24 fixed to and therefore movable with the hammer 11. This latter also carries a spring 25^a having a free end which when desired, may be engaged with a pin 25 on the pawl 23 so as to raise this to a point at which its free end will not come into engagement with the ratchet cam 14 when the cylinder 5 and hammer 11 are reciprocated.

Under conditions of use a series of jacquard cards extends around the cylinder 2 in the well known manner and each of these cards may be different or at least, not made in duplicate as would ordinarily be required for making square mesh lace. When the machine is in use the cylinder-carrying pistons 5 are constantly reciprocated but with my mechanism the cylinder 2 is turned only on alternate strokes of said pistons. This is due to the fact that when the various parts are in the positions shown in Fig. 1, with the roller 18 of the clawker 7 resting upon the high part of one of the teeth 15 of the star cam 13, the outward stroke of the cylinder pistons 5 with the hammer 11 causes the dog 23 to engage one of the teeth of the ratchet cam 14 and turn it through an angle of 45° or one-eighth of a revolution. The resulting 45° rotation of the cam 13 thereupon moves the high part 15 of one of its teeth out of engagement with the roller 18, so that the clawker 7 drops sufficiently to cause the inclined end of its hook to ride upon one of the pins 6 of the cylinder 2 as it with said pistons 5 are moved back. The body of said hook thereafter falls into engagement with said pin so that on the next outward movement of the piston 5 with the cylinder 2, the pin 6 is so held by the hook of the clawker 7 that said cylinder is caused to make a quarter revolution and thereby advance the chain of jacquard cards to the extent of one card.

Immediately after such turning of the cylinder 2, the dog 23 engages another tooth of the ratchet cam 14, turning it with the star cam 13 in such manner that the roller or pin 18 of the clawker 7 rides up the incline of a second tooth of said latter cam and finally comes to rest at the top of the same in a position in which its hook cannot engage the pins 6 of the cylinder. Consequently on the succeeding inward and outward movements of the pistons 5 and cylinder 2, the latter is not engaged by the hook of the clawker and is therefore not turned, although owing to the fact that on

said outward movement the dog 23 engages another one of the teeth of the ratchet cam 14, it with the star cam 13 is so turned as to again permit the clawker to drop into position to coöperate with a second pin of the cylinder 2 and give it another 90° movement on the succeeding outward stroke. Obviously therefore, the chain of jacquard cards is advanced only on alternate strokes of the cylinder so that each card is operated on twice by its coöoperating pins as required.

If for any reason it should be desired to have the cylinder turned at every stroke of its pistons 5, the spring 25^a would be engaged with the pin 25 of the pawl or dog 23 so that this latter would be held up toward the hammer 11 in such a position that its free end could not engage the teeth of the ratchet 14 and under operating conditions said ratchet would occupy a position with the roller 18 of the clawker between two of the teeth of the cam 13 with the result that it would operate on a pin 6 of the cylinder in the customary manner to cause a quarter turn thereof on each stroke of the pistons. The dog or holding pawl 19 acts to prevent accidental turning of the two cams and to insure their proper positioning under operating conditions and it is obvious that if it is desired to reverse the direction of rotation of the cylinder, the clawker 7 may be held by any suitable means such as a hook 7^a in its upper or inoperative position while the clawker 8 is connected to cause its hook under the action of a spring 8^a to engage the pins and intermittently turn the cylinder 2 as the pistons are reciprocated in the manner well known to those skilled in the art. It should be noted that the form and positioning of the star cam 13 on the stud 12 as well as the position of the dog 23 on the hammer may be varied without departing from my invention, since it is immaterial at what part of the stroke of the piston 5 said pawl is caused to act on its cam to raise or release the clawker 7.

I claim:

1. In jacquard mechanism for looms, the combination of a reciprocating cylinder; a clawker; a cam for raising the clawker into an inoperative position; a ratchet for said cam mounted with the latter in position to directly operate on the clawker; and a pawl for intermittently turning the ratchet and cam to cause the clawker to operate on the cylinder on alternate strokes only.

2. In jacquard mechanism for looms, the combination of a reciprocating card cylinder; a clawker; a projection on the clawker; a cam mounted adjacent the clawker in position to operate on said projection thereof; a ratchet fixed to said cam; a dog for preventing rotation of the ratchet in one direction; and a reciprocating pawl opera-

tive on the ratchet to cause the cam to alternately move the clawker into and release it from an inoperative position.

3. In jacquard mechanism for looms, the combination of a reciprocating cylinder; a clawker; a hammer; a toothed cam for raising the clawker into an inoperative position; a ratchet having twice as many teeth as said cam and fixed to the same; with a 10 pawl mounted on the hammer in position to engage the ratchet at every stroke of the cylinder.

4. In jacquard mechanism for looms, the combination of a frame; a piston; a recip-

rocating cylinder; a clawker; a hammer; 15 a projection on the clawker; a toothed cam mounted on the frame under the clawker in position to coöperate with the projection thereof; a ratchet having double the number of teeth of the cam and fixed thereto; 20 a holding dog on the frame operative to prevent rotation of the cam and ratchet in one direction; and a pawl on the hammer placed to engage the ratchet at each reciprocation of the cylinder. 25

In witness whereof I affix my signature.

ADAM F. SCHULER.
